UNITED STATES PATENT OFFICE.

ERNEST R. ERICKSON, OF DES MOINES, IOWA, ASSIGNOR TO C. E. ERICKSON COMPANY, INC., OF DES MOINES, IOWA.

DESIGN FOR A COMBINED TOOTHBRUSH AND PASTE HOLDER.

Application filed May 15, 1922. Serial No. 2,255. Term of patent 7 years.

To all whom it may concern:

Be it known that I, ERNEST R. ERICKSON, a citizen of the United States, and a resident of Des Moines, in the county of Polk and State of Iowa, have invented a certain new, original, and ornamental Design for a Combined Toothbrush and Paste Holder, of which the following is a specification, reference being had to the accompanying drawing, forming part thereof.

The figure is a perspective view of my tooth brush and paste holder.

I claim:

The ornamental design for a combined toothbrush and paste holder, as shown and described.

ERNEST R. ERICKSON.
